UNITED STATES PATENT OFFICE.

JOHN KREMENOK, OF RACINE, WISCONSIN.

AIR-SHIP.

No. 826,038.

Specification of Letters Patent.

Patented July 17, 1906.

Application filed December 17, 1904. Serial No. 237,290.

To all whom it may concern:

Be it known that I, JOHN KREMENOK, a citizen of the United States, residing at Racine, in the county of Racine and State of Wisconsin, have invented a new and useful 5 Air-Ship, of which the following is a specification.

This invention relates to improvements in air-ships, and has for its principal object to 10 provide an aerial vessel which may be readily propelled and guided in any desired direction.

A further object of the invention is to provide a strongly-braced but light framework for the support of the propeller and steering- 15 rudders and for sustaining the car and all of its parts from the balloon or gas-field.

A still further object of the invention is to provide a novel form of propeller and to provide means whereby the air drawn into the 20 propeller-casing may be utilized in ascending and descending.

A still further object of the invention is to provide a novel form of forward steering-rudder which may be shifted to various positions 25 in order to guide the vessel to the right or left both in ascending and descending.

A still further object of the invention is to provide a novel form of aerial vessel in which the gas-field is provided with means for the 30 escape of excess gas without danger of reduction of the volume below a predetermined extent.

With these and other objects in view, as will more fully hereinafter appear, the invention 35 consists in certain novel features of construction and arrangement of parts, herein- after fully described, illustrated in the accom- 40 companying drawings, and particularly pointed out in the appended claims, it being, un- derstood that various changes in the form proportions, size, and minor details of the structure may be made without departing from the spirit or sacrificing any of the ad- 45 vantages of the invention.

In the accompanying drawings, Figure 1 is 50 a side elevation of an air-ship constructed in accordance with the invention. Fig. 2 is a detail perspective view of the various parts of the frame. Fig. 3 is a similar view of the forward portion of the frame, illustrating particularly the arrangement of the cables and the adjustment of the forward steering- 55 rudder. Fig. 4 is a detail sectional view showing one of the adjusting devices of the

forward steering-rudder. Fig. 5 is a sectional elevation, on an enlarged scale, of a portion of the car, illustrating principally the arrangement of the propelling-engine and the steering-wheels. Fig. 6 is a detail sectional view of a portion of the propeller and showing also a portion of a propeller-casing. Fig. 7 is a detail plan view of the rudder-post and arms of the rear rudder.

Similar numerals of reference are employed to indicate corresponding parts throughout 65 the several figures of the drawings.

In carrying out the invention a cylindrical balloon 10 is constructed of silk or the like, and this is protected by an outer covering of linen. The balloon is preferably in the form 70 of a long cylinder having pointed ends, and when in position its longitudinal axis is disposed at an acute angle to the horizontal lines of the frame and the horizontal plane of the propeller, so that in ascending the under surface of the balloon will act as an aeroplane. 75

To the opposite sides of the balloon are secured two metallic tubes 12, at the opposite ends of which are secured lighter and smaller tubes 13, that are extended toward the front 80 and rear ends of said balloon and are connected to the linen covering by suitable loops or rings. The tubes 12 are provided with a number of perforations 14 to permit adjustment of the bolts 15, which connect said tubes 85 to hangers 16, four of the latter being employed, and these being connected to the four corners of the car 17.

The skeleton of the car is formed, preferably, of light metallic strips connected to 90 form a basket-like structure of convenient width and depth, and in this basket is an engine 18 of any suitable character, preferably an internal combustion - engine, and the basket also carries a number of steering- 95 wheels 19, 19', 20, and 21, having suitable drums of ordinary construction, over which pass tiller-ropes or cables that are connected to the forward and aft rudders. At the front of the car is arranged a pair of vertical rods 23, and at the rear is a similar pair of rods 24, these being connected at the top by a longitudinally-disposed brace-bar 25, which also constitutes one of the members of an octagonal frame 26, within which the propeller is arranged. The propeller-inclosing frame is formed of three octagonal frame structures 27, that are connected at inter-

vals by longitudinal brace-bars 28, the lower-most of these bars 28' being secured firmly to a portion of the basket or cage, while two of the upper members are rigidly secured at 5 their opposite ends to the hangers 16.

The frame is inclosed by a casing formed of linen or other light material, which may be coated with oil to prevent the passage of air. The opposite ends of the casing are of course left open for the passage of a current of air. The framework is also provided with bearings for the support of a longitudinally-disposed shaft 30, to which a number of collars 31 are rigidly secured. From the 5 collars projects a series of ribs 32, each of which is curved or bent by means of a cable or rod 33, secured to the outer end of the rib and its inner end to that side of the collar opposite the point of attachment of said rib, thus forming a very rigid structure for the support of a propeller-blade 34, which may be formed of any suitable material. The propeller-blade is helical in form, and its shaft is connected by a belt 35 to the engine or other source of power, air being sucked in at the front of the casing and forced from the rear end thereof, so that within the casing there is a strong current of air which when discharged at the rear of the vessel will cause 5 forward movement of the latter. To the rear bars 24 of the frame are secured rearwardly-extending brackets 38, to which is pivoted a rudder-frame 39 of a height equal at least to the diameter of the propeller. This rudder-frame is covered by canvas, linen, or other suitable material. To the lower end of the rudder-post are secured arms 40, from which extend tiller-rods 41 to the drum of the steering-wheel 21, and if the rudder is shifted either to the right or left the volume of air directed against its angularly-presented surface by the propeller will cause immediate turning of the vessel.

On the two forward tubes or bars 23 of the frame is mounted a vertically-slidable block 42, to the upper and lower sides of which are connected cables 43, running to a steering-wheel 20, so that the block may be positively raised or lowered and any suitable locking means may be employed to retain it in adjusted position. In this block is journaled a short shaft 44, at the inner end of which is a worm-wheel 45, intermeshing with a worm 46, that is feathered on a vertically-disposed shaft 47, adapted to suitable bearings in the frame. The lower end of the shaft 47 is provided with a bevel-gear 50, with which meshes a second bevel-gear 51, that is secured to a handled crank-shaft 52, the crank being within convenient reach of an attendant at the forward end of the basket or cage. Connected to the front end of the shaft 44 by the universal joint 53 is a T 54, and to said T are secured three tubes or rods 55, 56, and 57. The forward tube extends outward

for a considerable distance and carries a second smaller tube 58 in order to reduce the weight where great strength is not essential. These four tubes support a triangular rudder 59.

The frame is provided with four pulleys or sheaves 60, 61, 62, and 63, the sheaves 60 and 61 being arranged opposite each other in vertical alinement and the sheaves 62 and 63 being disposed in horizontal alinement. Over the sheaves 60 and 61 passes a cable 65, that is extended to the frame of the steering-wheel 19'. By turning this wheel in one direction or the other the rudder may be adjusted at any desired angle to the horizontal and employed as an aeroplane to assist in either upward or downward movement of the vessel, as may be desired.

Extending over the sheaves 62 and 63 is a cable 67, having its central portion wound around the drum of the steering-wheel 19 and its opposite ends being connected, together with the ends of the cable 65, to a swiveled head 68 at the outer end of the tube 58. By turning the steering-wheel 19 in the proper direction the point of the rudder may be directed either to the right or to the left to assist the main aft rudder in directing the course of the vessel.

The worm-gearing is so arranged that the forward rudder may be turned to either a vertical or a horizontal position, and in starting it will preferably be disposed in the horizontal position or at an angle to the horizontal to assist the vessel in ascending. After reaching the desired height the rudder may be turned to the vertical position and is utilized for steering purposes.

In ascending and descending the forward rudder is also of value in that it may be adjusted vertically for the purpose of directing a greater or less quantity of air from either the upper or the lower side of the rudder to the propeller. By properly adjusting the cables 43 the rear end of the forward rudder may be elevated almost to the top of the propeller-casing, so all of the air which enters the latter or the greater part of the air will be from below the rudder, and thus will assist materially in the ascension, owing to the current of air created on the under side of said rudder, and in the same manner by lowering the rudder the current of air may be caused to strike on top of the same, and thus assist in the descending movement.

To the lower portion of the balloon is connected a filling-tube 70, through which the necessary gas may be supplied, and at a point near the top of the balloon is an escape-valve 71, operated by lines 72 from the basket.

It is advisable in many cases to provide for the escape of surplus gas without danger of permitting the escape of more than a predetermined volume, and for this purpose there is joined to the under side of the main bal-

loon a supplemental compartment 73, and at the lowermost end of said compartment the partition between it and the balloon is provided with an opening 74, through which gas from the balloon may be passed and rise toward the larger upper end of said compartment. In the upper front wall of the compartment 73 is an escape-valve 74', which may be operated by lines 75 from the vessel, 10 said lines extending over suitable guiding-sheaves 76, carried by the hangers 16.

With a device of this character it is obvious that by proper manipulation of the forward and aft rudders and by rotating the 15 propeller the vessel may be directed to the right or left and may be made to ascend or descend, being at all times under the control of the operator.

Having thus described the invention, what 20 is claimed is—

1. In an air-ship, a propeller, a casing within which the propeller is arranged, a rudder at the front of the casing, and means for raising and lowering the rear end of the rudder 25 to vary the volume of air passing into the casing from the upper and lower sides of the rudder, and means for varying the angular position of said rudder.

2. In an air-ship, a propeller, and a casing 30 within which the propeller is contained, and a revolute rudder arranged at the front of the casing and adjustable to present its rear cross-bar either in a horizontal or vertical plane, means for adjusting the front end of the rudder either vertically or horizontally 35 for steering up or down, or to the right or left, and means for raising and lowering the rear end of the rudder to vary the volume of air passing into the casing from the upper 40 and lower sides of the rudder when the latter is in the horizontal position.

3. In an air-ship, a propeller, an open-ended propeller-casing, a vertically-adjustable block at the front end of the casing, a rudder-frame, a universal joint connecting the rudder-frame to the block, said rudder-frame 45 being adjustable to present the frame at any angle, and means for adjusting the front end

of the rudder-frame to direct the course of the ship.

4. In an air-ship, a propeller, a propeller-casing open at its front and rear ends, a vertically-adjustable block at the front end of the casing, a rudder-frame, a universal joint connecting the rudder to the block, and 50 means for adjusting the position of said frame. 55

5. The combination in an air-ship, of a propeller, a propeller-casing open at its front and rear end, a vertically-adjustable block at the front end of the casing, a spindle carried 60 by the block, a rudder-frame, a universal joint connecting the rudder-frame to the spindle, a worm-wheel carried by said spindle, a worm intermeshing with said worm-wheel, and means for turning the worm. 65

6. The combination in an air-ship, of a propeller-shaft, collars on said shaft, a plurality of curved ribs projecting from the collars and arranged in a helical series, tension members connecting the outer ends of the 70 ribs to said collars, thereby maintaining the ribs in curved positions, a helical propeller-strip carried by said ribs, and an open-ended casing within which the propeller is arranged. 75

7. The combination in an air-ship, of an elongated gas-field, a basket or car arranged below the gas-field, and in a plane at an acute angle to the axial plane of the gas-field, telescopically-adjustable tubes secured to the opposite sides of the gas-field, front and rear 80 pairs of hangers depending from said tubes and secured at their lower ends to the basket or car, a propeller-casing disposed in a horizontal plane above the basket or car, a propeller in said casing, front and rear rudders 85 at the ends of the casing, means for operating said rudders, and means for adjusting the vertical position of the front rudder.

In testimony that I claim the foregoing as my own I have hereto affixed my signature 90 in the presence of two witnesses.

JOHN KREMENOK.
